SUPPORTING DEVICE

Emma Wally Crum, Poughkeepsie, N. Y.

Application February 12, 1938, Serial No. 190,166

1 Claim. (Cl. 24—81)

This invention relates to supporting devices adapted to be selectively attached to structures of different size and to retain articles, such as, for example, the cords for annunciator-control buttons, light control cables and switches, and other small articles, in positions convenient for use.

The principal object of the invention is to provide a simple and inexpensive supporting device which may be attached to a mattress, the side rail or head of a bed, a table, or other article of furniture and which is adapted to hold and releasably retain an electric cord or cable or other article.

Another object of the invention is to provide a supporting device which may be readily attached to structures which vary greatly in size, such as, for example, articles of furniture.

Other objects of the invention will become apparent from a description of a typical form of device embodying the invention.

In its preferred form, the invention is embodied in a device having a plurality of cooperating resilient clamping portions which are spaced apart different distances, said clamping portions being urged toward each other whereby they may engage on opposite sides of supporting structures of widely different thicknesses to retain the device in a desired position. One form of the device is provided with a resilient hook-like portion adapted to receive and resiliently retain small articles such as electrical cables or conductors, pencils, thermometers and the like.

The device has particular usefulness in hospitals as a support for an annunciator cord and switch in that it may be readily attached to and retained on a thick article, such as the edge of a mattress or on a thin supporting element such as the head of the bed. The hook-like portion is adapted to retain the annunciator switch in a position which is readily accessible to the patient. The device may be located directly adjacent a hand of the patient so that the switch may be reached substantially without effort on the part of the patient.

The device may likewise be used with great facility as a support for the cord of an electrical iron in that it may be attached to an ironing board or other convenient construction in any desired position.

For a better understanding of the present invention, reference may be had to the accompanying drawing, in which:

Figure 1 is a perspective view of a typical form

of device embodying the invention attached to a portion of a mattress; and

Figure 2 is a perspective view of the device attached to a portion of the head of a bed.

The form of device illustrated in the drawing consists of two opposed jaw members 10 and 11 which are formed of spaced interconnected portions of a single wire. The device is of generally double S-shaped formation consisting of a small hook portion 12 spaced slightly from the jaw 11 and the main body portion of the S member which consists of the jaws 10 and 11 and suitable resilient connecting portions 13 of the wire. Each connecting portion 13 of the wire may be provided with a coiled torsion spring 14 which normally tends to force the outer ends of jaws 10 and 11 toward each other.

To form the device, a single wire may be bent at its center into a U-shaped formation. The closed end of the U is bent into parallelism with the free ends of the wire to form the short hook portion 12 and the jaw 11. The free ends of the wire are bent at substantially right angles to and away from hook 12 and jaw 11 to form connecting portions 13. The torsion springs 14 are formed in the connecting portions 13 and the wire is again bent to form jaw 10 and complete the S-shaped structure. The ends of the wire may be bent toward each other and connected to form a unitary device. The supporting device may then be tempered to render it resilient. In practice, the length of the connecting portions 13 exceeds the transverse dimension of the device whereby structures may be gripped between the jaws 10 and 11 which are too thick to be inserted between the connecting portions 13.

The device may be clamped, as illustrated in Figure 1, on the edge of a mattress 15 with the hook portion 12 adjacent either the top or the bottom of the mattress. The hook portion 12 and the cooperating jaw 11 are so spaced that they will resiliently receive and retain a small article such as an electric cord 16 which is provided with a push button type of switch 17 for energizing an annunciator or for controlling electric lights and the like. Likewise, other small articles may, if desired, be disposed beneath the hook portion 12 in order to retain them in a convenient position for removal by the occupant of the bed.

The torsion springs 14 and the connecting portions 13 of the wires are normally spaced slightly apart but are resiliently urged toward each other by means of the tension of the wire, whereby, if

desired, the entire device may be resiliently attached to a structure of smaller dimension than a mattress, such as the head of a bed. As illustrated in Figure 2, the connecting portions 13 and 5 torsion springs 14 may be disposed on opposite sides of the head of a bed with the hook formed by the loop 12 and a clamping portion 11 in position to receive the cord 16 of the switch 17.

The device is thus capable of use with supporting structures of comparatively great or of comparatively small thickness and will readily support many kinds of small devices in a desired convenient location.

The device, as illustrated, is formed of a single 15 piece of wire but if desired a plurality of pieces may be used and welded together or connected in any other manner as may be desired to form a unitary construction.

The word "wire" used herein is intended to 20 cover wire of circular or non-circular cross section, thin strips of metal or other similar spring material. If desired, the device may be provided with rubber covering vulcanized thereto or slipped thereover in order to prevent scarring 25 of the article upon which the device is supported. The device is simple in construction and yet is highly effective in use and has many advantages, such as convenience of application to the supporting structure and substantially universal 30 applicability to supporting structures of varying thickness or size.

While the device is illustrated as having clamping portions 10 and 11 thereof spaced at a comparatively great distance apart and the springs 35 14 and connecting portions 13 spaced at a comparatively short distance apart, these proportions may be varied in accordance with the usage to which the device is to be put. Likewise, while the hook or loop portion 12 is illustrated as being 40 substantially half the length of the clamping portion 11, it should be understood that these

proportions may be varied as, for example, by making the hook of smaller or greater dimensions than illustrated. Therefore, the embodiment of the invention disclosed should be considered as illustrative only and not as limiting 5 the scope of the following claim.

As clearly shown in Fig. 2 the substantially parallel lengths of wire 10 and 11 which form the jaws are connected together to form the ends of the jaws by portions 19, 20, of the same resilient wire and that connecting portion 19 which is reversed and forms the hook 12 thus is made to serve as a spring for urging those portions 13 which connect the jaws together, toward each other to yieldingly grip a supporting object. As 15 the hook 12 is only reversed part way of the jaw which it overlies it does not prevent such engagement of the connecting portions over the support.

I claim:

A holder for the purposes set forth made of 20 resilient wire and comprising a pair of opposed jaws formed of spaced substantially parallel lengths of wire connected together across the ends of the jaws by resilient wire portions, resilient wire portions connecting said spaced 25 lengths of wire which form the jaws and urging the ends of the jaws inwardly toward each other, the resilient connecting wire portion forming the end of one of the jaws being turned back part 30 way over that jaw in the form of an overlying hook and forming a spring for urging the connecting wire portions toward each other to enable 35 said connecting wire portions to receive between them and to yieldingly grip over a supporting member and said resilient connecting wire portions enabling the opposing jaws to receive between them and to yieldingly grip a supporting object.

EMMA WYLLY CRUM. 40
